UNITED STATES PATENT OFFICE

169,913

LAMINATED PLASTIC SHEET

George C. Rassman, Pittsfield, Mass., assignor to
General Electric Company, a corporation of
New York

Application April 19, 1952, Serial No. 19,398

Term of patent 14 years

(Cl. D87—3)

To all whom it may concern:

Be it known that I, George C. Rassman, a citizen of the United States, residing at Pittsfield, in the county of Berkshire, Commonwealth of Massachusetts, have invented a new, original, and ornamental Design for a Laminated Plastic Sheet, of which the following is a specification, reference being had to the accompanying drawing, forming a part thereof.

The figure is a plan view of a complete laminated plastic sheet showing my new design.

I claim:

The ornamental design for a laminated plastic sheet, as shown.

GEORGE C. RASSMAN.
